CLAIM

The ornamental design for a product applicator container, as shown and described.

DESCRIPTION

FIG. 1 is an upper front perspective view of product applicator container showing a first embodiment of the new design;

FIG. 2 is a lower rear perspective view of the invention illustrated in FIG. 1;

FIG. 3 is a front elevation view of the invention illustrated in FIG. 1;

FIG. 4 is a rear elevation view of the invention illustrated in FIG. 1;

FIG. 5 is a right side elevation view of the invention illustrated in FIG. 1;

FIG. 6 is a left side elevation view of the invention illustrated in FIG. 1;

FIG. 7 is a top plan view of the invention illustrated in FIG. 1; and,

FIG. 8 is a bottom plan view of the invention illustrated in FIG. 1.

1 Claim, 7 Drawing Sheets
